UNITED STATES PATENT OFFICE.

HARRY BARRINGER COX, OF HARTFORD, CONNECTICUT.

THERMO-ELECTRIC GENERATOR.

SPECIFICATION forming part of Letters Patent No. 434,500, dated August 19, 1890.

Application filed June 13, 1890. Serial No. 355,300. (No model.)

To all whom it may concern:

Be it known that I, HARRY BARRINGER COX, of Hartford, in the county of Hartford and State of Connecticut, have invented certain new and useful Improvements in Thermo-Electric Generators; and I do hereby declare that the following is a full, clear, and exact description of the invention, which will enable others skilled in the art to which it appertains to make and use the same, reference being had to the accompanying drawing, and to the letters and figures of reference marked thereon, which form part of this specification.

This invention relates to certain improvements in thermo-electric generators.

The object of the invention is to improve the construction of thermo-electric generators, particularly to increase the heating-surface thereof.

These objects are accomplished by, and this invention consists in, certain novel features of construction, and in combinations of parts more fully described hereinafter, and particularly pointed out in the claims.

The accompanying drawing represents a plan of a pile.

This invention is an improvement on the generator of my application for thermo-electric generators, dated January 9, 1890, Serial No. 336,339, wherein the pile is composed of a series of rings laid one on the other, with insulating material between the rings, being clamped together to form a tight cylinder, each ring being composed of a series of couples united together, and all the rings being electrically connected in one circuit. A fire-pot or other source of heat is located at one end of the cylindrical pile, and the interior of the pile, subject to the heat of the fire and formed by the inner ends of the elements, is coated with fire-proof cement or other suitable material.

In the drawing, *a* and *b* indicate the unlike elements of each couple composing the ring shown, all connected in the one circuit, as shown, and having terminals *1* *2*. Each large element is provided with one or more conductors or radiators *c*, electrically connected with the same between the hot and cold junctions thereof and extending out in the direction of the cold junctions. The inner ends

of the elements are coated with fire-proof cement or other suitable material. It should be observed that the inner ends of these couples or elements are so shaped and placed together that it enables me to so coat the same with cement that the interior of the cylinder forms a longitudinally fluted or corrugated cylinder, as shown, each large element being beveled off on one side of its inner end, as shown, so that the grooves or corrugations extend in between the ends of the adjoining couples. This corrugated or fluted surface very materially improves the draft and exposes to the heated products of combustion a much larger surface for the absorption of the heat.

In practice in the construction of a generator, as herein described, a series of rings, such as illustrated, are piled one on the other and separated by suitable insulating material and firmly bound together. The interior surface and spaces between the elements is walled up with some fire-proof cement or clay. In coating the face of the generator a sufficient thickness of cement is applied; but it is aimed to follow the outline of the interior as originally formed. After this cement has been placed, as described, it is allowed to set or harden, then a slow heat is applied, and finally a high temperature which has the effect of vitrifying the same, and making a hard, compact, and fire-proof coating for the interior.

The conductors *c* produce a fall in thermic potential in the circuit.

It is evident that various slight changes might be made in the form and arrangement of the parts described without departing from the spirit and scope of my invention; hence I do not wish to limit myself to the precise construction herein set forth.

What I claim is—

1. A thermo-electric generator having its surface exposed to the heat coated with fire-proof material and fluted, corrugated, or otherwise irregular, substantially as and for the purpose set forth.
2. A thermo-electric pile having the inner ends of its elements coated with vitrified cement or clay, substantially as described.
3. A cylindrical thermo-pile having its in-

ner surface coated with fire-proof material and fluted longitudinally, as set forth.

4. A thermo-electric generator having the inner surface of the couples embedded in or 5 coated with fire-proof material, and the conductors or radiators in the circuit and extending outwardly from said couples between their hot and cold junctions to produce a fall in thermic potential, substantially as described.

In testimony that I claim the foregoing as 10 my own I affix my signature in presence of two witnesses.

HARRY BARRINGER COX.
